UNITED STATES PATENT OFFICE.

CHARLES AUTH AND NEWTON L. SCHLOSS, OF NEW YORK, N. Y.

DESIGN FOR A LAMP-GLOBE.

46,555.

Specification for Design.

Patented Oct. 20, 1914.

Application filed August 17, 1914. Serial No. 857,273. Term of patent 7 years.

To all whom it may concern:

Be it known that we, CHARLES AUTH and NEWTON L. SCHLOSS, citizens of the United States, residing at New York, in the county of New York and State of New York, have invented a new, original, and ornamental Design for a Lamp-Globe, of which the following is a specification, reference being had to the accompanying drawing, forming part thereof.

Figure 1 is a side elevation, and Fig. 2 is

an end view of a lamp globe, showing our new design.

We claim:—

The ornamental design for a lamp globe as shown.

CHARLES AUTH.
NEWTON L. SCHLOSS.

In presence of—

CHAS. OTT,
H. T. KELLERMAN.
